VACUUM CLEANER

Oscar M. Anderson and Nils T. Almquist, New Britain, Conn., assignors to Landers, Frary & Clark, New Britain, Conn., a corporation of Connecticut

Application December 9, 1938, Serial No. 244,830

5 Claims. (Cl. 183—51)

The present invention relates to vacuum cleaners, and more particularly to an improved vacuum cleaner of the tank type.

The present invention aims to provide an improved vacuum cleaner which is constructed of a minimum number of parts, is economically manufactured and assembled, can be readily taken apart for inspection, cleaning or repair, is rugged in construction, and can withstand any rough usage to which it may be subjected.

A further object of the invention is to provide an improved vacuum cleaner casing and a closure for holding the dust bag in the casing to prevent the accumulation of dust at the exterior of the bag and subsequent escape of dust while removing the dust bag.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the accompanying drawings:

Figure 1 is a longitudinal sectional view of a vacuum cleaner, illustrating an embodiment of the invention;

Fig. 2 is a sectional view, illustrating an improved closure cap for the dust bag end of the vacuum cleaner casing;

Fig. 3 is a sectional view similar to Fig. 2, illustrating the closure removed from the casing;

Fig. 4 is a detailed fragmentary sectional view of the open end of the dust bag, illustrating a mounting and sealing ring for the dust bag;

Fig. 5 is an end view, partly in section, illustrating an improved construction for mounting the vacuum creating unit in the casing;

Fig. 6 is a perspective view of a bushing forming a part of the mounting construction shown in Fig. 5; and

Fig. 7 is an enlarged sectional view of a gasket for providing a seal between the vacuum creating end and dust bag end of the casing.

Referring to the drawings, and more particularly to Fig. 1, there is shown a vacuum cleaner of the portable tank type comprising, generally, a casing 11; a vacuum creating unit at one end of the casing, including a motor 12, a rotary suction pump or exhaust fan 14, and an air filter device 15; a cylindrical dust bag 16 mounted at the other end of the casing; a cap 17 serving as a closure for the dust bag end of the casing and as a coupling for attaching a vacuum hose or

the like; and clasps 18 on the casing for securing the cap 17.

The casing preferably is substantially cylindrical adjacent the dust bag end and at this end is provided with an annular zone 19 slightly reduced in diameter for receiving the cap and an inwardly extending flange 20 for mounting the dust bag, as about to be described.

The dust bag has an open end provided with 10 a mounting ring 23 (Fig. 4) comprising a radially outwardly extending bead or enlargement 24 at one end thereof, a groove 25 adjacent the bead, and a flange 26 at the other end bent outwardly at right angles with respect to the ring. The ring further is provided with a suitable rubber gasket 27 having the flange 26 embedded therein. The dust bag preferably is attached to the mounting ring by inserting the outer or free edge 28 of the bag through the ring, then folding the same outwardly over the bead 24 and holding it in the groove 25 by suitable wires 29 tied about the ring (Fig. 4).

The end closure or cap 17 comprises an outer member 30 and an inner member 31 secured to the outer member. The outer member is substantially dome-shaped and has at its lower end an outwardly extending flange 35 adapted to be engaged by the clasps 18, and a cylindrical skirt portion 36 extending downwardly from the flange and adapted to be telescoped over the reduced zone 19 of the casing. At the apex of the dome-shaped member there is provided an aperture 37 and an inwardly extending vacuum hose attaching sleeve 38 terminating in a radially inwardly facing flange 39 for attaching the inner cap member.

The inner cap member 31 has a substantially cylindrical side wall 41 and a substantially conical bottom 42 provided with a centrally located aperture defined by a flange 45. The flange 45 is alignable with and adapted to abut the flange 39 of the tubular sleeve 38 of the outer closure member.

The inner and outer cap members may be secured by connecting the flanges 39 and 45 in any suitable manner, but preferably, a tubular connecting sleeve 46 is utilized. The sleeve has, adjacent one end thereof, an outwardly extending fold or shoulder 47 engaging one side of the flange 45 of the inner member, and has an end portion 49 extending through the apertures of the flanges 39 and 45 and bent radially outwardly and forced into engagement with the flange 39 of the tubular sleeve of the outer member.

The other end 48 of the sleeve 46 extends up-

wardly from the bottom of the inner cap member and serves to prevent dust from passing through the aperture 31 in the event that the casing is held in inverted position, as shown in Fig. 2, after the vacuum hose has been removed from the coupling sleeve.

When the inner and outer members are thus secured, the junction of the bottom and cylindrical side wall of the inner member is adapted to abut the inner wall of the outer dome shaped member at 50, and the cylindrical side wall 41 of the inner member cooperates with the inner side of the wall of the outer member to provide a suitable annular groove 51 for receiving the edge 28 of the bag, as about to be described.

When the vacuum cleaner is assembled, the bag is in the casing with one side of the gasket 21 of the mounting ring seated on the flange 20 at the end of the casing, and the skirt 36 of the outer cap member is telescoped over the reduced end zone 19 of the casing with its outwardly extending flange 35 fitting against the other side of the gasket. When the cap is attached in this manner, the edge 28 of the bag folded over the mounting ring extends into the groove 51 provided by the inner and outer cap members, and the free end of the side wall 41 of the inner cap member is telescoped into the open end of the bag (Fig. 2). Preferably, the side wall 41 fits snugly into the open end of the bag to provide a secure seal adapted to prevent the passage of dust to the exterior of the mounting ring. This keeps the exterior of the ring and bag clean at all times and facilitates removing the cap and the bag from the casing without spilling any dust or dirt or getting dirty hands.

For example, when it is desired to empty the bag after using the vacuum cleaner, any dust which is in the inner cap member, as shown in Fig. 2, is directed into the bag by placing the casing in upright position with the dust bag end thereof facing upwardly. The cap may then be removed, as shown in Fig. 3, with complete assurance that all the dust has been emptied into the bag. The bag may be lifted out of the casing by manually engaging the gasket 21, which also is clean and free from dust, and may be emptied in the usual manner.

The end of the casing wherein the vacuum creating unit is mounted has a circumferential shoulder 55 and a substantially conical portion or nose 56 terminating in a cylindrical flange 57 adapted to serve as a support for one end of the vacuum creating unit (Figs. 1 and 5).

The motor 12 and the pump 14 of the vacuum creating unit are assembled as a unit prior to being placed in the casing, preferably, by securing the motor to one end of the pump housing 58. The filter device 15 also is connected to form part of the unit by securing it to the other end of the pump housing and comprises a perforated shield 60 having a forwardly projecting flange 61 provided with a seat 62, and a filter disc 64 (Fig. 1) contained in suitable frame members 65 held together by an annular gasket 66 fitted against the seat 62.

The vacuum creating unit further is provided with suitable mounting means for supporting and securing it in the casing. At the forward end of the unit an annular rubber gasket 67 is secured intermediate the perforated shield 60 of the filter device and the pump housing 58 and has its outer periphery in engagement with the inner peripheral wall of the casing. The gasket 67 has a circumferential rim portion 68 of substan-

tially the same diameter as the inside of the wall of the casing and also has a relatively thin peripheral flange 69 normally extending outwardly therefrom and being of greater diameter than the inside wall of the casing (Fig. 7). When the vacuum creating unit is placed into the casing, the flange 69 is flexed into alignment with the inner surface of the casing (Fig. 1) and the gasket 67 thus provides a support for the forward end of the unit and creates a seal preventing air from leaking into the low pressure end of the casing whereby a relatively high vacuum is created. The other end of the vacuum creating unit carries a rubber bushing 70 (Figs. 5 and 6) provided with an annular groove 71 for mounting a spider, about to be described.

The spider comprises a plurality of strip members 75, for example, three, each having an arcuate portion 76 cooperating to provide a collar seated in the groove of the bushing. Each of the spider members has a radially extending leg 77 provided with a foot portion 79 engaging the inner periphery of the flange 57 at the end of the nose. The spider members are adapted to be secured to the nose or conical portion 56 by suitable removable screws 80 extending through apertures 81 in the flange and threaded into the foot portions.

The nose is covered by a removably mounted cap 85 attached to the casing by suitable bolts or screws 86 extending through apertures 87 in the shoulder and held in place by nuts 89. The cap has an inwardly extending tubular sleeve portion 90 which serves as a coupling for an air pressure hose and also as a support for mounting a tubular screen 92 for preventing objects from being inserted into the motor unit. When the cap is secured to the casing, one end of the screen is telescoped over the tubular sleeve portion of the cap and the other end bears against the outwardly facing wall 94 of the bushing, whereby the cap and bushing cooperate to hold it in place.

Upon removal of the cap, the electrical connections for the motor are readily accessible through the spaces between the spider legs and can be inspected and repaired without taking the entire vacuum cleaner apart. Also, by mounting the vacuum creating unit in the simplified manner noted above, the unit can be easily removed from the casing by unscrewing the three screws 80 securing the legs of the spider to the flange at the end of the nose 56. All the connecting means for securing the unit in the casing are in full view of the workmen assembling or taking the vacuum cleaner apart, thus facilitating assembly, inspection and repair.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim as our invention:

1. In combination, a vacuum cleaner casing having an open end and provided with a circumferential radially inwardly extending flange, a

dust bag in said casing, having an open end, a mounting ring for said dust bag including a gasket fitting against the said casing flange and a forwardly projecting portion having the dust bag mounted thereon, and a cap having an outer member provided with a skirt telescoped over the open end of said casing and having a flange fitting against said gasket and compressing same against said casing flange to provide an air impervious seal between the cover member and the flange, said cap having an inner member provided with a side wall spaced inwardly from the inner wall of said outer cap member, said side wall being telescoped into said mounting ring and fitting snugly against the inner side walls of said dust bag at its open end to enclose the forwardly injecting portion of the mounting ring and the dust bag between the inner and outer cap members and maintain same dust free at all times.

2. In combination, a vacuum cleaner having a casing with an open end and provided with a circumferential inwardly extending flange, a sealing ring positioned against said flange, a dust bag extending rearwardly from said sealing member and a removable cap member securable to said casing and comprising inner and outer spaced apart members, said outer member telescoping over the casing and provided with an inwardly extending circumferential flange engaging said sealing member and compressing same against said casing flange and said inner member telescoping within said bag to enclose the end thereof and maintain said bag and sealing member dust free at all times.

3. In a vacuum cleaner, a cylindrical casing having an open end, a sealing member positioned at said open end of the casing, a dust bag extending rearwardly from said sealing member, a closure for the open end of said casing comprising

5 inner and outer spaced apart cylindrical members, said outer member adapted to telescope over the casing and said inner member adapted to telescope within said bag and cooperating means carried by the open end of said casing and the outer member of said cover for securing said sealing member therebetween.

10 4. In combination, a vacuum cleaner casing having an open end, a sealing member positioned adjacent said open end, a bag extending rearwardly from said sealing member, a cover member for closing said open end comprising inner and outer spaced apart members, said outer member telescoping over said casing and said inner member telescoping within said bag to completely enclose said sealing member and the forward end of the bag therebetween, said cover member being provided with a centrally arranged inlet tube, said tube extending through said inner member and for a substantial distance beyond same to provide a dust catching trough at the forward end of said casing.

15 5. In combination a vacuum cleaner having a casing with an open end and provided with a circumferential inwardly extending flange, a sealing ring positioned against said flange, a dust bag extending rearwardly from said sealing member and a removable cap member securable to said casing and comprising inner and outer 20 members, said outer member telescoping over the casing and provided with an inwardly extending circumferential flange engaging said sealing member and compressing same against said casing flange and said inner member inter-engaging the end of said bag to completely enclose the sealing ring between the inner and outer cap members and bag and maintain same dust free at all times.
